HYDROMASSAGE UNIT FOR A BATHTUB

Roy A. Jacuzzi, Moraga, and Peter L. Kosta, Lafayette,
Calif., assignors to Jacuzzi Research, Inc.

Filed July 23, 1973, Ser. No. 381,860

Term of patent 14 years

Int. Cl. D24—01

U.S. Cl. D83—1 C

FIG. 1

FIG. 3

FIG. 4

FIG. 5

FIG. 1 is a perspective view of a hydromassage unit showing our new design;

FIG. 2 is a rear view in elevation of said device;

FIG. 3 is a top plan view of the device of FIG. 1;

FIG. 4 is an end elevation as seen in the direction of line 4—4 of FIG. 3;

FIG. 5 is an end view in elevation of the said device taken in the direction of 5—5 of FIG. 3, and

FIG. 6 is a bottom plan view of the device of FIG. 1, taken in the direction 6—6 of FIG. 2.

We claim:

The ornamental design for a hydromassage unit for a bathtub, as shown.
